(57) **CLAIM**

The ornamental design for a weighted cup, as shown and described.

DESCRIPTION

FIG. 1 is a perspective view of a weighted cup, showing my new design;

FIG. 2 is a side elevation view thereof;

FIG. 3 is a top plan view thereof;

FIG. 4 is a bottom plan view thereof; and,

FIG. 5 is a sectional view thereof, taken along line 5-5 of FIG. 3.

The broken lines shown in the drawings depict a portion of the weighted cup that forms no part of the claimed design.

1 Claim, 5 Drawing Sheets
